FIG. 5

FIG. 2

FIG. 3

FIG. 4

FIG. 1 is a perspective view of a combined brush and sponge, partly broken away, showing my new design;

FIG. 2 is a side elevational view thereof;

FIG. 3 is an end elevational view thereof;

FIG. 4 is an end elevational view of a modified form thereof, shown fragmentarily for ease of illustration; and

FIG. 5 is a sectional view taken along the line 5—5 of FIG. 3.

The ends not shown are substantially identical in appearance to those which are shown. The broken lines shown in FIG. 2 represent the bristles omitted for convenience of illustration.

This is a continuation-in-part of design application Ser. No. 225,703, filed Feb. 11, 1972, now U.S. design Pat. No. 227,718.

I claim:

The ornamental design for a combined brush and sponge, substantially as shown and described.
